UNITED STATES PATENT OFFICE.

EDGAR D. JOHNSTON, OF CONNERSVILLE, INDIANA, ASSIGNOR TO THE P. H.
& F. M. ROOTS COMPANY, OF SAME PLACE.

DESIGN FOR A HEAD FOR ROTARY PUMPS.

SPECIFICATION forming part of Design No. 25,461, dated May 5, 1896.

Application filed March 30, 1896. Serial No. 585,496. Term of patent 14 years.

To all whom it may concern:

Be it known that I, EDGAR D. JOHNSTON, of Connerville, Fayette county, Indiana, have invented and produced a new and useful Design for a Head for Rotary Pumps, of which the following is a specification, reference being had to the accompanying drawing, showing the same in perspective.

The leading features of my design consist of a plate from one surface of which projects a pair of bosses, each having a longitudinal perforation rectangular at its base and arched at its top, and braces projecting from the face of the plate and joining the exterior of the bosses.

In the drawing, A is the plate; B B, the bosses projecting parallel with each other from one face of the plate; C, the longitudinal perforations in the bosses, having rectangular braces projecting from the face of the plate and joining the exterior of the bosses.

What I claim is—

The design for a head for a rotary pump, substantially as shown and described.

EDGAR D. JOHNSTON.
